UNITED STATES PATENT OFFICE.

MICHAEL F. BROGAN, OF LAWRENCE, MASSACHUSETTS, ASSIGNEE TO UNITED SHOE MACHINERY COMPANY, OF PATERSON, NEW JERSEY, A CORPORATION OF NEW JERSEY.

SEWING-MACHINE.

1,071,026.

Specification of Letters Patent.

Patented Aug. 26, 1913.

Application filed December 4, 1911. Serial No. 663,701.

To all whom it may concern:

Be it known that I, MICHAEL F. BROGAN, a citizen of the United States, residing at Lawrence, in the county of Essex and State 5 of Massachusetts, have invented certain new and useful Improvements in Sewing-Machines; and I do hereby declare the following to be a full, clear, and exact description of the invention, such as will enable others 10 skilled in the art to which it appertains to make and use the same.

This invention relates to lock stitch sole sewing machines of the class employing a curved hook needle.

15 In the manufacture of McKay shoes a false welt is often sewed to the upper outer portion of the sole before the sole is incorporated in the shoe, so that the shoe, when complete, resembles a Goodyear shoe. In 20 sewing the false welt to the sole, it is essential that the sole and welt be accurately guided at the sewing point so that the welt may be attached to the sole in the proper position with relation thereto and so that 25 the line of stitches may be properly positioned with relation to the edges of the sole and welt. It is desirable to employ a lock stitch curved hook needle machine in sewing the false welt to the sole in order that the 30 stitching may resemble as closely as possible the stitching of the outseam of a Goodyear shoe. It is also desirable in certain cases that the distance of the line of stitches from the edge of the sole and welt be varied as in 35 passing from the forepart of the shoe to the shank and from the shank to the forepart so that a McKay shoe may be made to resemble a Goodyear shoe having a "Baltimore" or "Scotch" edge.

40 The object of the present invention is to provide an attachment for a lock stitch curved hook needle shoe sewing machine for use in sewing a false welt to a sole before the sole is incorporated in the shoe, by which 45 the sole and welt may be accurately guided and by which the distance of the line of stitches from the edges of the sole and welt may be varied at the will of the operator during the continued operation of the machine.

With the above object in view, the invention consists of certain constructions, arrangements and combinations of parts hereinafter described and claimed, the advan-

tages of which will be obvious to those skilled 55 in the art from the following description.

In the drawings illustrating the invention in the best form at present known to the inventor, Figure 1 is a front elevation of a portion of a sewing machine with the invention applied thereto showing a sole and false welt in the position to be sewed; Fig. 2 is a side elevation of the mechanism illustrated in Fig. 1, certain parts being shown in section; Fig. 3 is a detail plan view of the work table and the sole and welt gaging and guiding mechanism associated therewith showing a sole and false welt in position; Fig. 4 is a detail perspective view of the work table and associated parts and Fig. 5 is a sectional 70 view taken on the line 5—5 of Fig. 3, looking in the direction of the arrow.

The invention as illustrated in the accompanying drawings is applied to a curved hook needle sole sewing machine of the type 75 illustrated in the United States Patent to French and Meyer No. 473,870. The curved hook needle indicated at 1, the needle segment and guide, the awl 2, the awl segment 3 mounted on the upright 4, carried by the 80 feed slide, are all constructed, arranged and operated substantially as in the French and Meyer patent above referred to. The presser foot 5 is provided with a base 6, which is preferably somewhat larger than 85 the presser foot ordinarily used in this type of machine to engage and smooth out the welt in advance of the stitch forming mechanism. This presser foot is arranged and operated substantially as in the French and 90 Meyer patent.

In place of the usual work table, in the present embodiment of the invention, a work table constructed as shown particularly in Figs. 3 and 4 is employed. This work table 95 is constructed with a broad flat work supporting plate 7 to support the sole of the shoe and the false welt in a satisfactory manner during the sewing operation. A shank 8 is attached to this plate by which it 100 may be readily secured to the machine in place of the usual work table. A slot 9 for the needle and awl is formed in the rear portion of the plate 7. In sewing the false welt to the sole, the sole is placed tread side down 105 on the work table and the welt is laid on the upper surface of the sole adjacent the margin thereof.

10 indicates a gage for engaging the edges of the sole and welt adjacent the sewing mechanism. In the construction illustrated, this gage is formed by the upturned end of a 5 slide 11, extending forwardly from said gage and mounted on the under side of the work table preferably in advance of the needle. This slide is arranged to move forwardly and rearwardly on the work table to carry 10 the gage 10 toward and from the line of feed, and to this end is formed with slots 12 and 13 through which are passed shouldered screws 14 which are screwed into the work table. The slide is moved forwardly and rearwardly 15 on the work table by means of a manually operable lever 15 pivotally mounted on a stud 16 projecting downwardly from the under side of the table and arranged to swing across the slide. A block or shoulder 20 17 of substantially the same thickness as the slide is formed on the under side of the work table to provide a bearing surface for the pivoted end of the lever substantially even with the lower face of the slide. 25 A pin 18 projecting upwardly from the lever works in a slot 19 in the slide so that upon forward or rearward movements of the right hand end of the lever (Fig. 1) the slide is moved forwardly or rearwardly and the 30 gage 10 is moved toward or from the line of feed. The slide is cut away at 20 in order that in its movement it may not interfere with the awl or the needle. A dished spring plate 21 surrounding the stud 16 is interposed between the lever 15 and the block 17. The binding action of this spring plate holds the lever 15 and thereby the gage 10 in adjusted position.

A welt guide for guiding the false welt in 40 advance of the gage 10 is indicated at 22. This guide in the present embodiment of the invention is made up of two spring plates 23 and 24 bent in a form substantially U-shaped and fitting together in the manner 45 illustrated in Figs. 4 and 5. The forward extremities of the upper limbs of these plates are bent so as to coöperate to form a welt guiding passage 25. The plates 23 and 24 are arranged for relative adjustment to vary 50 the width of the welt guiding passage 25 so as to accommodate and accurately guide welts of varying widths. In the construction illustrated, this adjustment is provided for by forming the plate 23 with slots 26 55 through which pass screws 27 screwed into the plate 24. This arrangement permits the plate 23 to be adjusted longitudinally of the plate 24 upon loosening the screws 27 and the plates are held securely in adjusted position by tightening the said screws. The 60 welt guide is mounted on the under side of the work table with the limb thereof provided with the welt guiding passage overhanging the upper surface of the table as 65 shown in Fig. 4. In the construction illus-

trated, the lower limb of the plate 24 is extended some distance beyond the corresponding limb of the plate 23 and this extension of the plate 24 serves as a shank to attach the welt guide member to the under side of the work table. 70

In order to provide for the adjustment of the welt guide transversely of the vertical plane of the line of feed, slots 28 are formed in the member 24 and the said member is 75 attached to the work table by screws 29 passing through the said slots and screwed into the table. The welt guide is mounted a sufficient distance in advance of the gage 10 to allow the path of the welt to be varied on 80 its way to the sewing point in accordance with the changes in the position of the gage 10. The recess between the upper and lower limbs of the welt guide furnishes ample room for the manipulation of the sole. 85

In sewing a false welt to a sole the sole is placed with the tread side down on the work table and the welt is then led through the welt guide above the sole to the sewing point. The welt guide is adjusted so that for every 90 position which the gage 10 may assume in sewing the particular style of shoe under operation the rear face of the welt guide passage will occupy a position to the rear of the gage 10. This insures that the outer 95 edge of the welt will be brought up against the gage regardless of the position of the gage. The edge gage 10 may be adjusted to position the line of stitches at any desired distance from the edges of the sole and welt 100 at the beginning of the sewing and is held in adjusted position by the spring 21. When it is desired to vary the distance of the line of stitches from the edges of the sole and welt during the sewing operation the lever 105 15 is moved manually forwardly or rearwardly, thereby decreasing or increasing the distance of the line of stitches from the edges of the sole and welt as desired.

The attachment may be quickly and readily applied to a lock stitch curved hook needle machine of standard type merely by removing the usual work table and presser foot and attaching the work table and presser foot of the attachment. The work 110 table and the welt and sole gaging and guiding mechanism carried thereby may be employed with a presser foot of the usual dimensions, although the presser foot constructed as described has been found to be 115 120 more satisfactory.

Having explained the nature and object of the invention and having specifically described one form of mechanism in which it may be embodied, what is claimed is: 125

1. A lock stitch sole sewing machine having, in combination, stitch forming mechanism including a curved hook needle, a work table, a gage to engage the edges of the sole and welt, supporting means for said gage 130

mounted on the work table and extending forwardly of said gage, a welt guide mounted on the work table, and means under the control of the operator to move said gage with relation to the line of feed during the operation of the machine to vary the distance of the line of stitches from the edges of the sole and welt.

2. A lock stitch sole sewing machine having, in combination, stitch forming mechanism including a curved hook needle, a work table, a gage to engage the edges of the sole and welt, supporting means for said gage mounted on the under side of the work table and extending forwardly of said gage, a welt guide mounted on the said work table, and means to move said gage with relation to the line of feed during the continued operation of the machine to vary the distance of the line of stitches from the edges of the sole and welt.

3. A lock stitch sole sewing machine having, in combination, a work table, a gage for engaging the edges of the sole and welt, a slide supporting said gage mounted on the under side of the work table and extending forwardly of said gage, a welt guide mounted on said work table, and means under the control of the operator to operate said slide to move said gage with relation to the line of feed during the continued operation of the machine to vary the distance of the line of stitches from the edges of the sole and welt.

35 4. A lock stitch sole sewing machine having, in combination, a work table, a slide mounted on the under side of said work table in advance of the needle and movable thereon with relation to the line of feed, a gage carried by said slide arranged to engage the edges of the sole and welt, a welt guide mounted on the under side of the work table overhanging said table, and means under the control of the operator to move said gage with relation to the line of feed during the continued operation of the

machine to vary the distance of the line of stitches from the edges of the sole and welt.

5. A lock stitch sole sewing machine having, in combination, stitch forming mechanism including a curved hook needle, a work table, a slide mounted on the under side of the work table in advance of the needle, a gage to engage and guide the edges of the sole and welt carried by said slide, a manually operable lever mounted on the under side of the work table arranged to actuate said slide to carry the gage toward and from the line of feed, and a welt guide for guiding the welt in advance of the gage.

6. A lock stitch sole sewing machine having, in combination, stitch forming mechanism including a curved hook needle, a work table, a slide mounted on the under side of the work table in advance of the needle, a gage to engage and guide the edges of the sole and welt carried by said slide, a manually operable lever mounted on the under side of the work table and arranged to actuate the slide to carry the gage toward and from the line of feed, a stationary welt guide mounted on the under side of the work table and overhanging the same.

7. A lock stitch sole sewing machine having, in combination, stitch forming mechanism including a curved hook needle, a work table, an edge gage, a welt guide member attached to the under side of the work table and overhanging the upper surface thereof, the said member comprising two interfitting substantially U-shaped plates bent to form a welt guiding passage between them, said plates having provision for relative adjustment to vary the width of the welt guiding passage, and provision for adjusting said member on the work support transversely of the line of feed.
